(57) CLAIM

The ornamental design for a cabinet, as shown and described.

DESCRIPTION

In a preferred embodiment, the nature of this product is as a medicine cabinet having a side to side movable shelf system.

FIG. 1 is a top, left, front perspective view of a cabinet embodying my new design;

FIG. 2 is a front elevational view thereof;

FIG. 3 is a left side elevational view thereof, the right side elevational view being identical to the left side shown;

FIG. 4 is a top plan view thereof, the bottom plan view being identical thereto, albeit rotated 180 degrees;

FIG. 5 is a top, left, front perspective view thereof showing the deployment of the movable shelf system of the FIG. 1 cabinet, the left and right side elevational views of the FIG. 5 cabinet being identical to that shown in FIG. 3;

FIG. 6 is a front elevational view of the FIG. 5 cabinet;

FIG. 7 is a top plan view of the FIG. 5 cabinet, the bottom plan view being identical thereto, albeit rotated 180 degrees;

FIG. 9 is a top, left, front perspective view of the cabinet, albeit without the top panel shown in FIG. 1 so that the top shelf is visible, the front elevational view of the FIG. 9 cabinet being identical to that shown in FIG. 2, and the left and right side elevational views of the FIG. 9 cabinet being identical to that shown in FIG. 3.

The broken line representations of a drain groove in FIGS. 1, 2, 5, 6, 8, and 9, of shelves in FIGS. 5, 6, and 8, of rods in FIGS. 5, 6, and 8, and of holes in FIGS. 5 and 8, are for the purpose of illustration only, and form no part of the claimed design.
